CARTON

Charles M. Mapes, Henrico County, Va., assignor to Reynolds Metals Company, Richmond, Va., a corporation of Delaware

Filed Apr. 3, 1961, Ser. No. 64,571

Term of patent 14 years

(Cl. D52—2)

FIG. 1 is a front perspective view of a carton, showing my new design; and

FIG. 2 is a front perspective view thereof in open position.

The undisclosed rear, bottom, and end of the carton are substantially plain.

The characteristic feature of my design resides in the representation of a key located at one end of the closure flap, with the head portion of said key protruding beyond the end of the flap in the manner shown.

I claim:

The ornamental design for a carton, as shown and described.
